[57] CLAIM

The ornamental design for a sectioned sink mat, as shown and described.

DESCRIPTION

FIG. 1 is a front plan view of a sectioned sink mat showing our new design;

FIG. 2 is a top left front perspective view of a portion of the sectioned sink mat taken along line 2—2 of FIG. 1;

FIG. 3 is a front elevational view thereof, the rear elevational view being a mirror image;

FIG. 4 is a right side elevational view thereof, the left side elevational view being a mirror image; and,

FIG. 5 is a bottom plan view thereof.
